[57] CLAIM

The ornamental design for a fluorescent lamp, as shown and described.

DESCRIPTION

FIG. 1 is a front, top and right side perspective view of a fluorescent lamp showing our new design;

FIG. 2 is a top plan view thereof;

FIG. 3 is a front elevational view thereof, the rear being similar thereto;

FIG. 4 is a right elevational view thereof, the opposite side being a mirror image thereof; and

FIG. 5 is a bottom plan view thereof.

FIG. 1

FIG. 2

FIG. 3

FIG. 4

FIG. 5
